(57) **CLAIM**

The ornamental design for a wireless charger, as shown and described.

DESCRIPTION

FIG. 1 is a top, front, right side perspective view of a wireless charger, showing my new design closed, in a first configuration;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a bottom, rear, right side perspective view of the wireless charger of FIG. 1, shown open, in a second configuration and in a condition for use.

The broken lines depict portions of the wireless charger that form no part of the claimed design.

1 Claim, 9 Drawing Sheets
